Application January 27, 1938, Serial No. 187,132

12 Claims.

(Cl. 123—1)

The present invention relates generally to power units. More particularly the invention relates to that type of power unit which is mounted or suspended beneath the bottom of a railway car and comprises an internal combustion engine for driving an electric generator or other mechanism, a battery or set of inclined cylinders containing liquid fuel under pressure, such for example as propane, and a system for delivering at 5 a predetermined and uniform pressure fuel vapor from the tops of the cylinders to the engine for 10 operating purposes.

A unit of this type is usually used throughout the year especially when connected to drive an 15 electric generator, and encounters high as well as sub-zero atmospheric temperatures. When temperatures beneath 20° F. are encountered it has been found in practice that there is not sufficient pressure or vaporization of the liquid fuel 20 in the cylinders to supply the engine for full load operation.

One object of the invention is to provide a power unit of the type under consideration which is an improvement upon, and is more practical 25 and efficient than, previously designed units of like character by reason of the fact that it includes improved means for heating the fuel containing cylinders when low atmospheric temperatures are encountered in order to provide sufficient 30 vaporization of the liquid fuel to meet the requirements of the internal combustion engine during full load operation.

Another object of the invention is to provide a power unit of the last mentioned character in 35 which the heating means for the fuel containing cylinders comprises hollow drums which are arranged in heat exchange relation with the cylinders and have a pipe connection leading to them from the exhaust pipe of the engine and additional pipe means extending between them whereby the exhaust gases or products of combustion emanating from the engine during operation 40 thereof are caused to flow successively through the drums in order to heat them and cause them 45 in turn to heat the cylinders and vaporize the liquid fuel therein.

Another object of the invention is to provide a power unit of the type and character under consideration in which the system for delivering 50 at a predetermined and uniform pressure fuel vapor from the tops of the cylinders to the engine for operating purposes is so designed and constructed that it operates to supply fuel from the top of one of the cylinders until such cylinder 55 is empty and then from the top of the other cyl-

inder, and the pipe connection and additional pipe means whereby the exhaust gases or products of combustion emanating from the engine during operation of the latter are caused to flow successively through the drums are so designed 5 and arranged that the exhaust gases flow first through the heater for the one cylinder, that is, the cylinder which is first unloaded and then through the heater for the other cylinder to the end that greater efficiency is obtained in heating 10 the two cylinders.

Another object of the invention is to provide a power unit of the type and character last mentioned in which the pipe connection between the drums and the exhaust pipe of the engine embodies a fitting with a branch leading to the drums and a second branch leading to atmosphere and is provided with a butterfly type valve which may be shifted or manipulated back and forth between a position wherein it closes the branch 20 leading to the drums and effects opening of the other branch for the direct passage of exhaust gases from the engine to atmosphere and a position wherein it closes the second branch, that is, the branch leading to atmosphere and effects 25 opening of the branch leading to the drums for the passage or flow of the exhaust gases through the drums.

A further object of the invention is to provide a power unit of the last mentioned character 30 which embodies means for automatically controlling the valve so that the exhaust gases or products of combustion from the engine flow through the drums when the atmospheric temperature is 20° F. or below and flow directly to atmosphere 35 when the temperature of the atmosphere about the unit exceeds 20° F.

A still further object of the invention is to provide a power unit of the type under consideration which is generally of new and improved 40 design and effectively and efficiently fulfills its intended purpose.

Other objects of the invention and the various advantages and characteristics of the present power unit will be apparent from a consideration 45 of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a fragmentary side elevation of a 55

railway car having applied thereto a power unit embodying one form of the invention;

Figure 2 is an enlarged vertical transverse sectional view on the line 2-2 of Figure 1, illustrating the arrangement or position of the internal combustion engine and the liquid fuel containing cylinders and showing the pipe connection between the cylinder heating drums and the exhaust pipe of the engine;

10 Figure 3 is a diagrammatic type view of the system for supplying or delivering fuel vapor from the tops of the cylinders to the carburetor of the internal combustion engine;

15 Figure 4 is a vertical transverse sectional view illustrating the design and construction of the drums for heating the cylinders and showing in detail the branch equipped fitting in the pipe connection between the drums and the engine exhaust pipes and also the automatic valve controlling 20 means whereby the exhaust gases or products of combustion are controlled so that they flow to the drums during low atmospheric temperatures and to atmosphere during higher temperatures, that is, temperatures above 20° F.;

25 Figure 5 is a fragmentary sectional view through the cylinder heating drums, showing in detail the design and arrangement of the pipe or conduit means whereby the exhaust gases are caused to flow successively through the drums; 30 and

Figure 6 is a diagrammatic view of a second or modified form of power unit.

The power unit which is shown in Figures 1 to 5 inclusive of the drawings constitutes one embodiment of the invention and is illustrated in connection with a railway passenger car C as a medium for driving the generator for supplying electric current to the various electrical devices of the car. The car C is of conventional 35 design and comprises a body c with a pair of track engaging trucks c¹ at its ends. The car body c embodies a flat bottom c² which together with sides and a roof or top defines a compartment. The generator for the car C is located beneath 40 the bottom c² of the car body and has the reference character G applied thereto. The power unit is located or disposed beneath the bottom c², as shown in Figures 2 and 4, and comprises as the main or essential parts thereof an internal combustion engine 7, a pair of fuel cylinders 8 and 9, a system 10 for delivering fuel from the cylinders to the engine for operating purposes, and a pair of drums 11 and 12 for use in heating the cylinders for fuel vaporizing purposes during low 45 atmospheric temperatures.

The engine 7 is of standard design and embodies at one side thereof an intake manifold 13 and an exhaust manifold 14. The intake manifold 13 has a carburetor 15 for supplying it with 50 a mixture of fuel gas and air and embodies a plurality or set of branches which serve to supply the mixture into the cylinders of the engine via valve controlled inlet ports in the cylinder block. The exhaust manifold 14 is located above the 55 intake manifold 13 and has branches leading from the valve controlled outlet ports in the cylinder block of the engine. In addition it has a discharge or exhaust pipe 16 which extends along one side of the engine and includes a muffler 17. 60 The exhaust gases or products of combustion emanating from the engine during operation of the latter flow into the exhaust manifold 14 and thence through the muffler equipped exhaust pipe 16 as well understood in the art. The engine 7 65 is disposed in a transverse position beneath one

side of the bottom c² of the car body and is suitably encased and protected by a housing 18. It is connected through the medium of its crank shaft (not shown) to drive the generator G and is suitably cooled by a water jacket and radiator 5 (also not shown). The generator G is located at the inner end of the engine 7 and the casing thereof is bolted or otherwise fixedly secured to the adjacent portion of the engine. The housing 18 surrounds the bottom and sides of the engine 10 and is provided at the upper corners thereof with wheels 19 which are mounted on, and adapted to travel over, a pair of parallel laterally spaced tracks 20. The latter are suitably fixed or secured to the bottom c² of the car body and 15 embody extensible sections 21 which are adapted to be shifted outwardly beneath the adjacent side of the car body and permit the engine and generator to be wheeled in a horizontal rectilinear course from an operative position beneath 20 the bottom c² into an inspection or repair position wherein they are disposed outwardly and to one side of said bottom.

The fuel cylinders 8 and 9 are adapted to contain liquid fuel under pressure, such for example as propane. They are mounted or disposed in a housing 22 and comprise cylindrical side walls 23, bulged or rounded bottom walls 24, and top walls 25. The housing 22 is located in opposed relation with the internal combustion engine 7 and is suitably secured in a suspended manner from the bottom c² of the car body c. It is adapted to hold the fuel cylinders 8 and 9 in an inclined position with the top walls 25 facing outwards, as shown in Figure 4, and comprises an inclined bottom 26, a back wall 27, and a front wall 28. The bottom 26 is provided with cradles 29 which support the two fuel cylinders and hold them against lateral displacement. The front wall 28 is hinged at the lower margin thereof so 40 that it may be swung outwardly and downwardly into an open position. In such position the fuel cylinders are accessible for inspection, control or replacement purposes. The bulged bottom walls 24 of the cylinders are disposed adjacent to the lower portion of the back wall 27 of the housing 22 and have rings 30 welded or otherwise fixedly secured to the outer faces thereof. Said rings constitute feet whereby the cylinders may be stood in an upstanding position after removal 50 from the housing. The top walls 25 of the cylinders have reduced outwardly extending cylindrical necks 31 which are closed by plugs 32. These plugs are provided with outlet valves 33 and L-shaped pipes 34. The valves are exteriorly 55 disposed with respect to the plugs and are manipulable for opening and closing purposes when the front wall 28 of the housing 22 is in its open position. The L-shaped pipes 34 have short branches 35 and long branches 36. The short 60 branches are connected and lead to the outlet valves 33. The long branches 36 are so arranged that when the cylinders are in their proper or operative position in the housing they extend vertically and serve to conduct fuel vapor from the top portions of the interiors of the cylinders to the outlet valves 33. As a result of the arrangement of the long branches of the L-shaped pipes no liquid fuel within the cylinders can pass 65 to the outlet valves.

The system 10 serves as a medium for conducting the fuel vapor within the cylinders to the carburetor 15 and supplying it to the carburetor at a predetermined uniform pressure. It comprises a small pipe 37 and a large pipe 38. 75

The small pipe 37 leads from the cylinders 8 and 9 and is connected to receive fuel vapor from the cylinder 8 by way of a flexible tube 39, a reverse flow check valve 40, a pressure regulator 41, an excess flow valve 41^a, a globe valve 42, a pipe connection 43, and a T-fitting 44. The flexible tube 39 extends through a hole in the cylindrical neck 31 of the cylinder 8 and is connected to the outlet valve 33 for said cylinder. Under normal working conditions fuel vapor flows from the top portion of the interior of the cylinder 8 through the flexible tube 39, the reverse fluid check valve 40, the pressure regulator 41, the globe valve 42, the excess flow valve 41^a, the pipe connection 43 and the T-fitting 44 into the pipe 37. The pipe 37 is connected to receive fuel vapor from the cylinder 9 by way of a flexible tube 45, a reverse flow check valve 46, a pressure regulator 47, an excess flow valve 47^a, a globe valve 48, and a fitting 49. The flexible tube 45 extends through a hole in the neck 31 of the cylinder 9 and is connected to the outlet valve 33 of said cylinder so as to receive fuel vapor from the cylinder interior. During use of the unit fuel vapor flows from the cylinder 9 to the pipe 37 by way of the tube 45, the check valve 46, the pressure regulator 47, the excess flow valve 47^a, the globe valve 48, and the fitting 49. The pressure regulators 41 and 47 are differently set. For example, the regulator 41 is set at 15 pounds and the regulator 47 is set at 10 pounds. As a result of this arrangement gas vapor will first flow from the cylinder 8 through the system to the carburetor 15. As soon as the tank 8 becomes exhausted of fuel, the tank 9 automatically cuts into the system 10 as a result of the operation of the regulator 47 and serves as the fuel supply for the carburetor. The reverse flow check valves 40 and 46 serve to prevent fuel vapor from one cylinder passing to atmosphere in the event that the flexible tube for the other cylinder becomes severed or disconnected. The pipe 38 leads to the carburetor 15 and receives fuel vapor from the pipe 37 by way of a pressure regulator 50, an excess flow valve 51, and a fuel regulator and automatic shut-off 52. The pressure regulator is provided with a safety relief valve 53 and is connected to the discharge end of the pipe 37 by way of a fitting having a pressure gauge 54 connected thereto. The excess flow valve 51 is connected to the outlet of the pressure regulator 50 by way of a pipe connection 55 and is connected to the fuel regulator and automatic shut-off 52 by a flexible tube 56. The outlet of the fuel regulator and automatic shut-off is connected to the inlet end of the large pipe 38. When one of the cylinders is connected to supply fuel vapor to the pipe 37 and the internal combustion engine is started, the vapor passes successively through the pressure regulator 50, the excess flow valve 51, the fuel regulator and automatic shut-off 52, and the large pipe 38 to the carburetor 15. The carburetor, as well understood in the art, serves to mix air with the fuel vapor and form a combustible gaseous mixture which passes through the intake manifold 13 into the cylinders of the engine via the valve controlled inlet ports in the cylinder block of the engine. As the result of the action of the pressure regulator 50 the fuel vapor passes to the carburetor via the pipe 38 at a predetermined uniform pressure.

The drums 11 and 12 are associated with the cylinders 8 and 9 respectively and are adapted

during temperatures below 20° F., and as hereinafter described, to have the exhaust gases or products of combustion emanating from the exhaust pipe 16 of the internal combustion engine pass therethrough so that they serve to heat and vaporize the liquid fuel in the cylinders. At temperatures below 20° F. there is not sufficient vaporization of the liquid fuel in the cylinders to supply the engine under full load operation. By heating the cylinders when low atmospheric temperatures are encountered the necessary vaporization of the liquid in the cylinders takes place to create a sufficient fuel vapor supply for engine operating purposes. The two drums are interposed between the bottom walls 24 of the two cylinders and the back wall 27 of the housing 22 and comprise dished or concavo convex front walls 57, flat circular rear walls 58, and cylindrical side walls 59. The front walls are shaped conformably to and bear directly against the outer faces of the bulged bottom walls 24 and hence the drums are in direct heat exchange relation with the fuel cylinders. The rear walls 58 define with the front and side walls gas compartments 60 and are separated from the back walls 27 of the housing 22 by strips 61 of suitable heat insulating material. The side walls 59 serve to space apart the front and rear walls of the drums and fit within the rings 30 on the bottom walls of the fuel cylinders. The drum 11 is connected to receive the exhaust gases or products of combustion from the engine exhaust pipe by a pipe connection 62. The inlet end of this connection has a flared mouth 63 and the outlet end extends through a hole or aperture in the back wall 27 of the housing 22 and is connected to the rear wall 58 of the drum 11. The rear or discharge end of the exhaust pipe 16 fits within the mouth 63 and is adapted to slide into and out of engagement with the latter in response to shift of the engine 7 into and out of its operative position. The drum 11 is connected to the drum 12 by way of a pipe 64. This pipe extends horizontally, as shown in Figure 5, and is connected at one end thereof to the compartment 60 of the drum 11 by way of an elbow 65 and a nipple 66. The other end of the pipe 64 is connected to the gas compartment of the drum 12 by way of an elbow 67 and a pipe nipple 68. The gas compartment of the drum 12 is connected to atmosphere by way of an exhaust or outlet pipe 69. When the engine 7 is started at any time when low temperatures are encountered, that is, temperatures less than 20° F. and the exhaust gases are permitted to flow from the engine through the pipe connection 62 to the drum 11, such gases pass through the drum 11 and thence to the drum 12 via the pipe 64. After flowing through the compartment 60 of the drum 12 such gases are exhausted to atmosphere by way of the pipe 69. During successive travel of the gases through the two drums the fuel cylinders 8 and 9 are heated to such an extent that the liquid fuel in the cylinders vaporizes sufficiently to form an adequate vapor supply for the engine under full load conditions. Because the system 10 serves to unload the cylinders 8 and 9 in sequence, i. e., the cylinder 8 first and then the cylinder 9, and further, because the exhaust gases pass successively through the drums 11 and 12 maximum efficiency is obtained. This is attributable to the fact that when the cylinder 8 is unloading most of the heat from the exhaust gases or

products of combustion is absorbed by such cylinder since such gases or products of combustion flow first into the drum 11. When the cylinder 9 is unloading after emptying of the cylinder 8 there is little absorption of heat by the cylinder 8 due to no fuel vaporization therein. Because of the small amount of heat which is absorbed by the cylinder 8 after emptying of the latter there is sufficient heat in the exhaust gases passing through the drum 12 efficiently and effectively to vaporize the fuel in the cylinder 9. In order to permit drainage of condensation from the two drums 11 and 12, each drum is provided with a small drain pipe 70. The two pipes 70 are connected to the bottom portions of the drums and extend outwardly through the back wall 27 of the cylinder housing 22.

In order that the exhaust gases may be directly discharged to atmosphere when the temperature of the surrounding atmosphere is high, that is, above 20° F. and hence sufficient to effect the necessary vaporization of the liquid fuel in the cylinders 8 and 9, the pipe connection 62 is provided with a fitting 71. This fitting embodies a pair of branches 72 and 73 and has in the interior thereof a butterfly type valve 74 for controlling the flow of exhaust gases through the two branches. The branch 72 of the fitting leads to and communicates with the drum 11 and the branch 73 extends downwards and leads to atmosphere. The valve 74 is fixed to and radiates from a horizontal pivot shaft 75 and is adapted to swing back and forth between a position wherein it closes the branch 73 leading to atmosphere and opens the branch 72 leading to the drum 11 and a position wherein it closes the branch 72 and opens the branch 73. When the valve 74 is in such a position that it closes the branch 73, the exhaust gases emanating from the internal combustion engine 7 flow through the branch 72 and thence through the drums and produce the desired heating of the cylinders for fuel vaporizing purposes. When the valve 74 is in its other position, that is, in such position that the branch 72 is closed and the branch 73 is open, the exhaust gases flow directly to atmosphere and hence the heat thereof does not result in vaporization of the fuel in the cylinders 8 and 9.

The valve 74 is controlled or shifted automatically in response to temperature changes, by way of a heat or temperature responsive device 76. This device is positioned above the fitting 71, as shown in Figures 2 and 4, and comprises a bellows 77, a stem 78, an arm 79, and a protective casing 80. The bellows 77 is filled with any suitable readily expandable fluid and is fixed at one end thereof to the top wall of the casing 80. The stem 78 is connected to, and extends from, the other end of the bellows and projects through a hole in the bottom wall of the casing. The arm 79 is fixed to one end of the pivot shaft 75 and is pivotally connected at its distal end to the lower end of the stem 78. The bellows is so arranged and designed that when atmospheric temperatures in excess of 20° F. are encountered it expands and through the medium of the stem 78 and the arm 79 operates to hold the butterfly type valve 74 in such a position that it closes the branch 72 and opens the branch 73 for the direct passage of exhaust gases to atmosphere. When the temperature of the surrounding atmosphere drops to 20° F. or lower the bellows 77 is adapted to contract and operates through the medium of the aforementioned stem and arm to shift the valve

into its other position wherein it serves to close the branch 73 and open the branch 72 for the passage of exhaust gases to the drums 11 and 12. The device 76 constitutes or exemplifies simple means for automatically controlling the valve so that the exhaust gases or products of combustion from the engine flow through the drums when a low temperature is encountered and flow directly to atmosphere when temperatures in excess of 20° F. are encountered.

The operation of the unit is as follows: When one of the fuel tanks is connected to supply fuel vapor to the carburetor 15 of the engine and the engine is started, the fuel vapor flows through to the carburetor and after being mixed with air therein passes into the engine, as hereinbefore described. If the temperature of the surrounding atmosphere is low, that is 20° F. or less, and there is not sufficient pressure or vaporization of liquid fuel to supply the engine under full load the device 76 functions or operates to close the branch 73 of the fitting 71 and to control the fitting in such manner that the exhaust gases or products of combustion emanating from the exhaust pipe 16 of the engine flow into the drum 11. From such drum the gases flow into and through the drum 12 and thence to atmosphere and operate during their passage through the drums so to heat the cylinders as to vaporize the liquid and create sufficient pressure or fuel vapor properly to supply the engine with fuel under full load or working conditions. In the event that higher atmospheric temperatures are encountered, that is, temperatures in excess of 20° F. the device 76 operates to shift the valve 74 so as to close the branch 72 and open the branch 73 and hence results in the exhaust gases flowing directly to atmosphere. By providing the drums 8 and 9 and the device 76 for controlling the flow of exhaust gases to the drums the unit is adapted to operate efficiently when either high or extremely low temperatures are encountered. Under certain temperature conditions, the bellows will maintain the valve 74 in a position wherein the two branches are each part way open. When the valve is in such a position, a portion of the exhaust gases will be exhausted to atmosphere and the remainder will flow successively through the cylinder heating drums 11 and 12.

The aforementioned power unit effectively and efficiently fulfills its intended purpose and is characterized by the fact that it is usable throughout the year in places which are subject to wide temperature ranges. The heating means for the fuel cylinders is simple in design and hence may be employed without materially increasing the cost of the unit.

The power unit which is shown in Figure 6 of the drawings is generally the same as that of Figures 1 to 5, inclusive. It differs from the latter in that it embodies a pressure responsive device 81 instead of a temperature responsive device 76. Generally speaking the unit comprises an internal combustion engine 7^a, a pair of fuel cylinders 8^a and 9^a, a system 10^a for delivering fuel from the cylinders to the engine for operating purposes and a pair of drums 11^a and 12^a for use in heating the cylinders 8^a and 9^a for fuel vaporizing purposes when the rate of vaporization is such that insufficient fuel is delivered to the engine for full load operation. The engine has a carburetor 15^a and an exhaust pipe 16^a, the former being connected to receive fuel vapor from the cylinders 8^a and 9^a by way of the system 10^a and the latter serving as an outlet duct for the 75

exhaust gases or products of combustion. The exhaust pipe 16^a embodies a fitting 71^a having a pair of outlet branches 72^a and 73^a. The branch 73^a is controlled by means of a valve 74^a and is adapted when the valve is open to discharge the exhaust gases to atmosphere. The branch 72^a is connected to the drum 11^a by way of a pipe 62^a and operates when the valve 74^a is closed to deliver the products of combustion via the pipe 62^a to the drum 11^a. A pipe 64^a extends between the drums 11^a and 12^a and serves to conduct the products of combustion from the former to the latter. The drum 12^a embodies an outlet pipe 69^a and serves as a heater for the cylinder 9^a. The valve 74^a is controlled automatically by the pressure responsive device 81. The latter comprises a cylinder 82 and a piston 83. The piston is slidably mounted in the cylinder and is provided with a stem 84 which is connected by an arm 85 to the pivot shaft for the valve 74^a. The piston is adapted when reciprocated in one direction by the entry of fluid under pressure into the cylinder to open the valve 74^a so that the products of combustion emanating from the exhaust pipe are permitted to flow to atmosphere. A compression spring 86 is applied to the piston and operates when the pressure of the fluid in the cylinder decreases to retract the piston so that it closes the valve 74^a. The cylinder 82 is connected to receive fuel vapor from the cylinder 8^a by a pipe 87 and from the cylinder 9^a by a pipe 88. The pipe 87 has one end thereof connected to the system 10^a at a point between the reverse flow check valve and the pressure regulator for the cylinder 8^a and its other end connected to the cylinder 82. The pipe 88 is connected at one end thereof to the pipe 87 by way of a fitting 89 and has its other end connected to the discharge end of the flexible tube or hose leading from the cylinder 9^a. The pipe 87 includes a reverse flow check valve 90 at its inlet end. By way of the pipes 87 and 88 the cylinder 82 is connected to receive vapor from the two cylinders. When the vaporization of the liquid fuel in the cylinders is sufficient to supply the engine for a full load operation due to normal or high atmospheric temperature the fuel vapor because of its high pressure develops sufficient pressure within the cylinder 82 to move the piston against the force of the spring and cause it to hold the valve 74 in its open position. When the valve is in such position the products of combustion flow for the most part to atmosphere and but a small amount of exhaust gases, if any, flows through the drums 11^a and 12^a due to the fact that the pipe 62^a is of smaller cross-sectional area than the branch 73^a. When low atmospheric temperatures are encountered and the pressure of the fuel vapor of the system 10^a is hence reduced, the piston 83 is retracted by the spring 86, as hereinafter described, and the valve 74 is shifted into its closed position. In such position the products of combustion emanating from the exhaust pipe flow through the branch 72^a of the fittings 71^a and pass successively through the drums 11^a and 12^a and by their warming or heating action produce more ready vaporization of the fuel in the two cylinders.

Whereas the power unit has been described in connection with a railway car C and as a medium for driving the electric generator for the car it is to be understood that the unit may be employed in other capacities in connection with the drive of other equipment or apparatus. It is also to be understood that the invention is not to be restricted to the details set forth since these may

be modified within the scope of the appended claims, without departing from the spirit and scope of the invention.

Having thus described the invention, what I claim as new and desire to secure by Letters Patent is:

1. A power unit comprising in combination an engine having an intake manifold and an exhaust manifold and also having a carburetor connected to the intake manifold, a supply cylinder 10 adapted to be partially filled with vaporizable liquid fuel under pressure, means for supplying fuel vapor under pressure from the top portion of the interior of the container to the carburetor for delivery to the engine by way of the intake 15 manifold, a hollow heater disposed wholly exteriorly of the cylinder and having one wall thereof in heat exchange relation with the bottom portion of said cylinder, and means for automatically delivering the exhaust gases emanating from the 20 exhaust manifold to the heater when the normal vaporization of the fuel is insufficient to supply the engine for full load operation.

2. A power unit comprising in combination an internal combustion engine having an intake 25 manifold and an exhaust manifold and also having a supply carburetor connected to the intake manifold, a cylinder adapted to be partially filled with vaporizable liquid fuel under pressure, means for supplying fuel vapor under pressure 30 from the top portion of the interior of the cylinder to the carburetor for delivery to the engine via the intake manifold, a hollow heater disposed wholly exteriorly of the cylinder and having one wall thereof in heat exchange relation 35 with the bottom portion of said cylinder, a pipe connection leading from the exhaust manifold of the engine and having a fitting therein with a branch communicating with the heater and a second branch leading to atmosphere, a valve 40 mounted in the fitting so that it is shiftable into closed relation with either branch, and an automatic control device for the valve whereby the valve is shifted so as to close said second branch and open the first mentioned branch of the fitting 45 when the temperature of the surrounding atmosphere drops to a predetermined degree and is shifted to close said first mentioned branch and open the second mentioned branch when the temperature rises above such degree. 50

3. A power unit comprising in combination an internal combustion engine having an exhaust manifold therefor, a support in proximity to the engine, a supply cylinder for vaporizable liquid fuel under pressure mounted removably on said support, means operative when the cylinder is in place on the support to supply fuel vapor under pressure from the top portion of the cylinder to the engine for operating purposes, a hollow heater fixedly secured to the support and having 55 a wall arranged so that it is in heat exchange relation with the cylinder when the latter is in place, and means whereby the exhaust gases emanating from the exhaust manifold during operation of the engine may be circulated 60 through the heater in order to heat the cylinder and expedite vaporization of the liquid fuel therein. 65

4. A power unit comprising in combination an internal combustion engine having an exhaust 70 manifold, an inclined support, a supply cylinder for vaporizable liquid fuel under pressure, carried by the support in an inclined position and so that it may be readily removed therefrom when emptied, means operative when the cylin- 75

der is in place with respect to the support to supply fuel vapor under pressure from the top portion of the cylinder to the engine for operating purposes, a hollow heater fixedly secured to the lower portion of the support and having a wall arranged to abut directly against the cylinder when the latter is in place, and means whereby the exhaust gases emanating from the exhaust manifold during operation of the engine may be circulated through the heater in order to heat the cylinder and expedite vaporization of the liquid fuel therein.

5. A power unit comprising in combination an internal combustion engine having an exhaust manifold, an inclined housing having a door at the top thereof, a fuel supply cylinder for vaporizable liquid fuel under pressure, mounted in an inclined position in the housing and so that it may be removed from the housing upon opening 15 of the door, means operative when the cylinder is in place in the housing to supply fuel vapor under pressure from the top portion of the cylinder to the engine for operating purposes, a hollow heater fixedly secured in the bottom portion 20 of the housing and having a wall shaped conformably to the bottom of the cylinder and arranged to abut directly against the cylinder bottom when the cylinder is in place, and means for circulating the exhaust gases emanating from 25 the manifold through the heater.

6. A power unit comprising in combination, an internal combustion engine having an exhaust manifold therefor, a pair of supply cylinders for vaporizable liquid fuel under pressure, means 30 operative automatically to supply the engine first with fuel vapor under pressure from the top of one of the cylinders until such cylinder is emptied and then from the top of the other cylinder, a pair of hollow heaters associated respectively with and disposed in heat exchange relation with 35 said cylinders, and means for flowing exhaust gases from the exhaust manifold during operation of the engine first through the heater for the one cylinder and then through the heater for the other cylinder.

40 7. A power unit comprising in combination an engine having an intake manifold and an exhaust manifold and also having a carburetor connected to the intake manifold, a supply cylinder for vaporizable liquid fluid under pressure, means 45 for supplying fuel vapor under pressure from the top portion of the interior of the container to the carburetor for delivery to the engine by way of the intake manifold, a hollow heater disposed wholly exteriorly of the cylinder and having one 50 wall thereof in heat exchange relation with the cylinder, and means controlled by the pressure of the fuel vapor for automatically delivering exhaust gases from the exhaust manifold to the 55 heater when the normal vaporization of the fuel is insufficient to supply the engine for full load operation.

8. In combination, an inclined support, a supply cylinder for vaporizable liquid fuel under 60 pressure, carried by the support in an inclined position and so that it may be readily removed therefrom when empty, means operative when the cylinder is in place with respect to the sup-

port to supply fuel vapor under pressure from the top of the cylinder to a point of use, a hollow heater fixedly secured to the lower portion of the support and having a wall shaped conformable to the bottom of the cylinder and arranged to abut directly against the cylinder bottom when the cylinder is in place, and means for flowing a fluid type heating medium through the heater in order to heat the cylinder and expedite vaporization of the liquid fuel therein.

9. In combination, a pair of supply cylinders for vaporizable fuel under pressure, means operative automatically to supply to a point of use fuel vapor under pressure first from the top of one of the cylinders until such cylinder is empty 15 and then from the top of the other cylinder, a pair of hollow heaters associated respectively with and disposed in heat exchange relation with said cylinders, and means for flowing a fluid type heating medium first through the heater for the 20 one cylinder and then through the heater for the other cylinder.

10. In combination, a support, a supply cylinder for vaporizable liquid fuel under pressure mounted removably on said support, means operative when the cylinder is in place on the support to supply fuel vapor under pressure from the top portion of the cylinder to a point of use, a hollow heater fixedly secured to the support and having a wall arranged so that it is in heat exchange relation with the cylinder when the latter is in place, and means operative automatically in response to drop in temperature of the surrounding atmosphere to supply a fluid type heating medium to the heater.

11. In combination, a support, a supply cylinder for vaporizable liquid fuel under pressure mounted removably on said support, means operative when the cylinder is in place on the support to supply fuel vapor under pressure from the top portion of the cylinder to a point of use, a hollow heater fixedly secured to the support and having a wall arranged so that it is in heat exchange relation with the cylinder when the latter is in place, and means controlled automatically by the pressure of the fuel vapor for automatically delivering a fluid type heating medium to the heater.

12. A power unit comprising in combination an internal combustion engine having an intake manifold and an exhaust manifold and also having a carburetor connected to said intake manifold, a supply cylinder adapted to be partially filled with readily vaporizable liquid fuel under pressure, means for supplying fuel vapor under pressure from the top portion of the cylinder to the carburetor, a hollow heater disposed wholly exteriorly of the cylinder and having a wall thereof conforming to and in direct contact with the bottom portion of the cylinder, and means operative automatically in response to drop of the temperature of the surrounding atmosphere to a predetermined degree to deliver the exhaust gases emanating from the exhaust manifold of the engine into the heater in order to heat the cylinder and expedite vaporization of the fuel.
